COMBINATION SAFETY FUSE PULLER AND
HAND TOOL

Edward G. Nilsson, Brooklyn, N. Y.

Application May 2, 1932. Serial No. 608,676

6 Claims. (Cl. 81—3.8)

This invention relates to new and useful improvements in a combination safety fuse puller and hand tool.

The invention has for an object the construction of an article as mentioned which is characterized by the fact that it is substantially entirely constructed from insulating material and adapted to pull a fuse from its socket without any danger of short circuiting.

Furthermore, the invention also proposes the arrangement of novel means for causing the jaws to be opened and closed.

Furthermore, the invention proposes the construction of an article of the class described which is of simple durable construction, dependable in use and efficient in operation and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of an article constructed according to this invention.

Fig. 2 is a side elevational view of Fig. 1.

Fig. 3 is a fragmentary view similar to the upper portion of Fig. 2 but showing the jaws in an open position.

Fig. 4 is a horizontal sectional view taken on the line 4—4 of Fig. 3.

Fig. 5 is an enlarged fragmentary view of the upper portion of Fig. 8.

Fig. 6 is a side elevational view of Fig. 5.

Fig. 7 is a sectional view of an article constructed to a further modification of the invention.

Fig. 8 is a view similar to Fig. 2 but illustrating a modification.

The combination safety fuse puller and hand tool comprises a tubular body 10 formed with a pair of longitudinally opposite top slots 11 in which a pair of jaws 12 rest and protrude. A slide 13 is arranged within the tube 10. The jaws 12 and their inner ends pivotally connect upon the upper end of the slide 13, indicated by reference numeral 14. A cross pin 15 engages through an elongated slot 16 formed in the sides of the tube 10 and engaging within an opening in the slide 13 forming a construction whereby the slide may be moved by motion of the pin.

A means is provided for causing the jaws 12

to assume open positions when the slide 13 is moved upwards and particularly comprises a pin 17 extended across the top and of the tube in between the jaws 12 and immediately above tapered cam surfaces 18 adapted to cause separation of the jaws when the slide is moved upwards. The pin 17 is so located that in conjunction with the bottom ends of the slots 11 the jaws are caused to assume open positions as illustrated in Fig. 3. All of the parts preferably should be made from insulation material. This is particularly true of the jaws 12, the cross pin 17, the tube 10 and the slide 13. It can readily be seen that when thus constructed a fuse may be drawn from its socket without any danger whatsoever of short circuiting.

In Figs. 5 and 6 a modification of the invention has been disclosed in which provision has been made for varying within certain limits the opening action of the jaws 12. This variation is accomplished by the provision of means for changing the location of the transverse pin 17 which controls the opening of the jaws. The pin 17 extends through slots 20 formed in the sides of the tube 10 and fixed within lugs 21 immediately to the sides of the tube. These lugs project from a ring 22 slidably mounted upon the tube and held in various fixed positions by the provision of set screws 23 which threadedly engage through the ring and abut against the side of the tube. A change in the location of the cross pin 17 will correspondingly affect the opening of the jaws 12 when the slide 13 is raised.

In Fig. 7 another variation of the invention has been disclosed in which provision has been made for normally forcing the jaws to an open position and arranged in a manner so that closing is easily accomplished. In detail, this form of the invention comprises a tubular body 25 closed at the bottom end 26. At the top end this tubular body is formed with diametrically opposite slots 27 formed in from the top end. A slide 28 is arranged within the tube. A pair of jaws 29 are pivotally connected by a pintle pin 30 upon the slide 28 in a manner so that when the slide is raised the jaws may assume an open position and when lowered must assume a closed position as indicated by the dot and dash lines 31 due to the action of the jaws against the inside of the tube. Resilient means 32 is interposed between the jaws 29 and acts to normally urge the jaws into the open position.

A cross pin 33 engages through elongated slots 34 in the sides of the tube 25 and is fixedly connected with the slide 28. A spring 35 acts be-

tween the closed bottom 26 and a collar 36 secured upon the slide 28 so as to normally urge the slide into the raised position. The jaws 29, the tube 25, the cross pin 30 and the cross pin 33 should be made from insulating material.

The tool may be used for various other purposes besides the drawing of fuses from their sockets. In all cases, the device is manipulated to cause closing of the jaws for gripping the various articles.

While I have shown and described the preferred embodiment of my invention, it is to be understood that I do not limit myself to the precise construction herein disclosed and the right 15 is reserved to all changes and modifications coming within the scope of the invention as defined in the appended claims.

Having thus described my invention, what I claim as new, and desire to secure by United 20 States Letters Patent is:—

1. A combination safety fuse puller and hand tool, comprising a tubular body having diametrically opposite slots at the top end, a slide within said tubular body, a pair of jaws in said top slots 25 having the outer end touching and the inner ends extending into the tube and pivotally connecting with said slide, a cross pin through longitudinal slots in said tubular body and fixed in said slide, and means for causing opening of the jaws upon moving of the cross pin to move the slide towards the top end of the tube, said means being adjustable so as to cause opening of the edges at various predetermined positions of the slide.

2. A combination safety fuse puller and hand 35 tool, comprising a tubular body having diametrically opposite slots at the top end, a slide within said tubular body, a pair of jaws in said top slots having the outer ends touching and the inner ends extending into the tube and pivotally connecting with said slide, a cross pin through longitudinal slots in said tubular body and fixed in said slide, and means for causing opening of the 40 jaws upon moving of the cross pin to move the slides towards the top end of the tube, comprising a cross pin adjustably mounted through the tube near the top end and adapted to engage against inclined surfaces on the inner faces of the jaws and thus cause pivoting of the jaws.

3. A combination safety fuse puller and hand 50 tool, comprising a tubular body having diametrically opposite slots at the top end, a slide within said tubular body, a pair of jaws in said top slots having the outer ends touching and the inner ends extending into the tube and pivotally connecting with said slide, a cross pin through longitudinal slots in said tubular body and fixed in said slide, and means for causing opening of the 55 jaws upon moving of the cross pin to move the slides towards the top end of the tube, comprising a cross pin extending through the tube near the top end and adapted to engage against inclined surfaces on the inner faces of the jaws and thus cause pivoting of the jaws, and means for changing the position of said cross pin to control the jaw action.

4. A combination safety fuse puller and hand

tool, comprising a tubular body having diametrically opposite slots at the top end, a slide within said tubular body, a pair of jaws in said top slots having the outer ends touching and the inner ends extending into the tube and pivotally connecting with said slide, a cross pin through longitudinal slots in said tubular body and fixed in said slide, and means for causing opening of the jaws upon moving of the cross pin to move the slides towards the top end of the tube, comprising a cross pin extending through the tube near the top end and adapted to engage against inclined surfaces on the inner faces of the jaws and thus cause pivoting of the jaws, and means for changing the position of said cross pin to control the jaw action, comprising a ring slidably mounted on said tubular body, means for holding said ring in various positions, projections from said ring supporting the ends of said pin and said pin extending through longitudinal slots in said tubular body.
